FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE

REFRIGERATION UNIT

Application filed August 4, 1927. Serial No. 210,515.

This invention relates to refrigerating apparatus and aims to provide an efficient unit for such an apparatus. While the unit of this invention is more particularly adapted for use as an evaporating unit, it is to be understood that it can also be used as a condensing unit.

Refrigeration units such as the evaporating unit used for cooling showcases and the like have usually been installed in the lower portion or rear of the showcase or counter. I have found that the most advantageous place to install the unit in the counter or refrigeration compartment is in the upper part thereof in order that the compartment may be more uniformly cooled.

One of the principal difficulties which I encountered in providing a unit which is adapted to be installed in the upper portion of the counter was the fact that the ordinary units for this purpose took up too much space.

It is accordingly the primary object of this invention to provide a refrigeration unit which occupies a minimum of space.

It is also another object of this invention to provide a refrigerator more particularly a refrigerating counter in which is mounted a refrigeration unit, the unit being so arranged in the counter as to uniformly cool the same.

Other and further objects of this invention will be apparent as the same becomes better understood from an examination of the specification and claims in connection with the accompanying drawings, wherein

Fig. 1 is a fragmentary vertical section of a refrigerating counter provided with a refrigeration unit,

Fig. 2 is an enlarged fragmentary plan view of a refrigeration unit removed from the counter and

Fig. 3 is an enlarged fragmentary sectional view taken at the line 3—3 in Fig. 1.

Referring to the drawings more particularly, numeral 4 represents the interior of a refrigeration counter represented generally by the numeral 5.

Since cold air is heavier than comparative-
ly warm air, it is bound to settle in the coun-

ter and the most uniform cooling effect within the counter is obtained by mounting the evaporating unit of a closed circuit refrigeration system in the upper portion of the counter, for example as shown by the position of the unit represented generally by numeral 6 in Fig. 1. This unit consists of two headers 7 and 8 respectively mounted in juxtaposed relation to each other one above the other. These headers are closed at their respective opposite ends and the lower one, number 7, is connected by means of the pipe 9 to receive refrigerant from the system and the upper one number 8 is connected by means of a pipe 11 to the suction side of the compressor in the circuit. The lower header 7 is connected to the inlet ends of the lower portions 12 of a series of expansion coils or pipes and the upper header 8 is connected to the outlet ends of the upper portions 13 of said pipes. The two portions of said series of pipes are substantially parallel and horizontal and are so connected together at their ends remote from the headers that the two portions may be as closely together as possible in order to occupy a minimum of space, and at the same time present a gradual turn which will not be abrupt so as to offer excessive resistance to the flow of refrigerating medium therethrough.

Were the upper portion of each pipe or coil disposed directly above the lower portion, the bend in the pipe connecting the two portions would be so short that the bent portion of the pipe would be flattened in the bending operation and furthermore the bend would be so abrupt that it would impose excessive friction upon the flowing refrigerant thereby diminishing the efficiency of the machine. To obviate this objection, the bent portion of each pipe is positioned at an angle to the vertical so that the upper portion of one pipe is disposed over the lower portion of another pipe as will be apparent from Figs. 1 and 2. In order to permit this disposition of the pipes, the coils of each pair are made of different lengths so that the bend 10 of one coil will be disposed within the bend 20 of its companion coil. While this is the preferred arrangement, the bends if desired may ob-

viously be made still longer so that the upper portion of one coil extends laterally beyond the lower portion of its companion coil in which instance the upper and lower portions of companion coils would not be disposed in vertical alignment and if desired the bend might be made sufficiently long so that the upper portion of one coil would overlie the lower portion of the second coil at one side.

10 A unit constructed as above described possesses the advantage that it is of minimum depth from top to bottom so that it occupies a minimum of space in the counter while at the same time the bends in the coils are not so abrupt as to interfere with the circulation of the refrigerant. Furthermore by providing a unit, the depth of which is only slightly greater than the diameter of two pipes, the collection and formation of frost upon the 15 lower pipes upon the defrosting of the upper pipes is reduced to a minimum, whereas in units in which several pipes are superposed one above the other, the lowermost pipe collects the drippings from the upper pipes and 20 always carries considerable frost which interferes with the transference of heat units and correspondingly decreases the efficiency of the unit.

25 The unit may be very conveniently supported by means of transverse bars 14 suspended by hooks 15 connected to the top of the counter.

30 A cork pan 16 is suspended from beneath the unit by means of hooks 17 carried by the 35 pipes. This pan is adapted to collect moisture which may drop from the pipes of the unit. As shown in Fig. 1, the pan 16 is slightly inclined and provided with an outlet 18 in its lower side and any moisture flowing from 40 the outlet 18 is adapted to be caught in a drip cup carried on a bracket 21 mounted inside of the counter.

45 The drip pan 16 by its inclination also assists in the circulation of the air, the air passing downwardly to the right as viewed in Fig. 1 toward the lower portion of the counter and the comparatively warm air flowing upwardly beneath the pan and around the left edge thereof to the top of the counter.

50 I am aware that many changes may be made without departing from the principles of this invention. I therefore do not wish to be limited to the details shown or described.

I claim:

55 1. A refrigerating coil unit comprising an inlet header and an outlet header lying alongside, approximately contiguous and parallel thereto, and a plurality of pipe coils each formed as generally U-shaped loops, the plane of each loop being out of perpendicular to the longitudinal axes of said headers, the inlet and outlet ends of each loop being connected respectively to said headers at points which are spaced longitudinally with respect to each other on their respective headers, one U-

shaped coil having a shorter length than the other coils between the bottom of its loop and its ends, the plane of the last said loop intersecting the plane of another loop between the legs of both loops.

60 2. A refrigerating coil unit comprising an inlet header and an outlet header lying alongside, approximately contiguous and parallel thereto, and a plurality of pipe coils each formed into a straight legged U-shaped loop with its inlet and outlet ends connected respectively to the inlet and outlet headers, the middle portion of each coil being curved in an approximate U-shape aligned so that a plane passing through the center line of the 65 U-shaped portion of the pipe lies out of perpendicular with the longitudinal axes of said headers, the center lines of the connections of said coils and headers being too near each other to permit of forming the pipe coils into straight legged U-shapes with legs as close together as said center lines are without flattening of the coils in said loops, the plane of one of said pipe coils intersecting the plane of another.

65 In witness of the foregoing I affix my signature.
